UNITED STATES PATENT OFFICE.

JUSTUS R. KINNEY, OF JAMAICA PLAIN, MASSACHUSETTS.

RAZOR-BLADE HOLDER.

Application filed May 2, 1927. Serial No. 188,284.

This invention relates to razor blade holders and has for its object the production of a simple and inexpensive holder for razor blades to be used for a variety of purposes.

5 This object is attained by the device illustrated in the accompanying drawing.

For the purpose of illustrating the invention, one preferred form thereof is illustrated in the drawings, this form having 10 been found to give satisfactory and reliable results, although it is to be understood that the various instrumentalities of which the invention consists can be variously arranged and organized, and the invention is not 15 limited to the precise arrangement and organization of these instrumentalities as herein shown and described except as required by the scope of the appended claims.

Of the drawings:

20 Figure 1 represents a plan of a razor-blade holder embodying the principles of the present invention.

Figure 2 represents a longitudinal section of same on line 2, 2, on Fig. 1.

25 Figure 3 represents a perspective of the slideable member thereof.

Figure 4 represents a transverse section of the holder on line 4, 4, on Fig. 1, and

30 Figure 5 represents a transverse section of the holder on line 5, 5, on Fig. 1.

Similar characters indicated like parts throughout the several figures of the drawings.

In the drawings, 10 is a bottom plate of 35 spring metal having one end bent over upon itself to form a flap 11.

This flap 11 is provided with a plurality of projections 12 which are adapted to enter the usual holes in a razor blade 13 inserted 40 between the bottom plate 10 and said flap 11.

The projections 12 are formed integral with the flap 11 by forcing the metal downwardly by suitable dies provided for this purpose.

45 The bottom plate 10 is also provided on opposite sides with turned over edges 14, 15 which preferably are rounded to leave a smooth surface when the holder is grasped in the hand.

50 The turned over edge 14 extends the entire length of the bottom plate 10 and when the blade 13 is positioned in the holder its inactive edge projects below a portion of said edge as indicated in Fig. 1.

55 The turned over edge 15 extends only from one end of the bottom plate 10 to a

point adjacent the position of the razor blade 13 when disposed upon said bottom plate.

The projections 12 are formed near one 60 edge of the flap 11 so that when a razor blade is positioned between the bottom plate 10 and flap 11 the edge thereof to be used will project beyond the edge of the bottom plate 10, as indicated in Fig. 1. 65

The turned over edges 14, 15 stiffen the bottom plate 10 and form a rigid handle to be grasped by the user.

Beneath these turned over edges 14, 15 are the edges of a sliding member 16, the inner 70 end 17 of which is adapted to extend over the free end of the flap 11 and hold it firmly against the upper face of the blade 13.

By this means the blade 13 may be clamped firmly in position. 75

Preferably the sliding member 16 is provided with a raised portion 18 extending to the top of the turned over edges 14, 15, thereby providing a handle of considerable rigidity and free from any uneven surfaces. 80

The outer end of the slideable member 16 is provided with a downward extension 19 which coming into contact with the outer end of the bottom plate 10 limits the inward movement of said sliding member 16. 85

This downward extension 19 also provides a means whereby the member 16 may be seized and moved outwardly when it is desired to release the flap 11.

As the flap 11 is made of spring metal it 90 will move upwardly into the position indicated in Fig. 2 as soon as the member 16 has been moved sufficiently to release it.

When the flap 11 is released and has assumed the position indicated in Fig. 2 the 95 razor blade 13 may be removed from the holder and another blade substituted therefor.

This makes a very simple construction of 100 blade holder and as there are only two parts thereof which may be readily struck up from blanks without waste of material, it is very inexpensive to make.

When a blade 13 is positioned in the holder it may be used for a great variety of 105 purposes.

It is believed that the operation and many advantages of the invention will be understood without further description.

Having thus described my invention, I 110 claim:

1. A razor blade holder consisting of a

flat plate provided with oppositely disposed turned over side edges and having formed integral with one end a turned over flap provided with projections adapted to enter 5 the holes in a razor blade, and a slidable member between said turned over edges having an end adapted to overlap the inner end of said flap to clamp the blade in position.

2. A razor blade holder consisting of a flat plate provided with oppositely disposed turned over side edges and having formed integral with one end a turned over flap provided with projections adapted to enter the holes in a razor blade, and a slidable 10 member between said turned over edges having an end adapted to overlap the inner end of said flap to clamp the blade in position, said slidable member having a central raised portion extending lengthwise thereof between said turned over edges.

3. A razor blade holder consisting of a flat plate of spring metal having at one end a flap formed integral therewith and extending over said plate with a plurality of aligned 25 projections on its under face adapted to enter the holes in a razor blade, said plate having guide members extending lengthwise thereof, and a member slidable lengthwise of said guide members and adapted to overlap one end of said flap to clamp a blade to said plate.

4. A razor blade holder consisting of a long flat plate provided with a widened

blade-receiving portion at one end and having formed integral therewith a turned-over flap with depressed portions therein adapted to enter the holes in said blade, turned-over side edges on said plate, one terminating adjacent said widened portion and the other extending the entire length of the plate and forming at one end a protection for one blade edge, and a member slidable between said turned-over edges with one end normally overlapping the inner end of said flap.

5. A razor blade holder consisting of a long flat plate provided with a widened blade-receiving portion at one end and having formed integral therewith a turned-over flap with depressed portions therein adapted to enter the holes in said blade, turned-over side edges on said plate, one terminating adjacent said widened portion and the other extending the entire length of the plate and forming at one end a protection for one 55 blade edge, and a member slidable between said turned-over edges with one end normally overlapping the inner end of said flap, said member having a central raised portion with a flat outer surface in the same plane 60 with the outer surface of said turned-over side edges.

Signed by me at 746 Old South Bldg., Boston, Mass., this 29th day of April, 1927.

JUSTUS R. KINNEY.
